UNITED STATES PATENT OFFICE

102,598

DESIGN FOR A HOUSE TRAILER

Ralph H. Wise, South Bend, Ind., assignor to Edwards Iron Works, Incorporated, South
Bend, Ind., a corporation of Indiana

Application September 17, 1936, Serial No. 64,908

Term of patent 14 years

To all whom it may concern:

Be it known that I, Ralph H. Wise, a citizen of the United States of America and resident of South Bend, in the county of St. Joseph and State of Indiana, have invented a new, original, and ornamental Design for House Trailers, of which the following is a specification, reference being had to the accompanying drawings, forming a part thereof.

In the drawings, Fig. 1 is a perspective view of a house trailer showing the right side and rear of my new design. Fig. 2 is a perspective view showing the left side and rear thereof. Fig. 3 is a perspective view showing the front and left side thereof.

I claim:

The ornamental design for a house trailer as shown.

RALPH H. WISE.
